MEANS FOR WAVING HAIR

Hazel May McCalla, St. Louis, Mo.

Application June 19, 1939, Serial No. 279,793

7 Claims. (Cl. 132—11)

This invention relates generally to an improved means for dressing hair and more specifically to means for producing waves in hair such as those known as "finger waves," and by other names, the predominant object of the invention being to provide improved means for waving hair that includes one or more electrically heated combs which serve in use to give vastly improved results in hair dressing.

10 In accordance with the method now followed, finger waves are produced in hair by professional beauty operators by first shampooing the patron's hair and then, while the hair is wet from the shampooing, applying a solution to the hair which is characterized by the ability to cause the hair to remain wet for a considerable length of time. The solution mentioned is comprised basically of either gum arabic or pulverized seeds, such as quince seeds, and the solution is saturated 20 thoroughly through the hair, after which the hair is combed into position for waving.

In producing finger waves in hair so prepared for waving the first finger of the operator's left hand holds the portion of the hair being waved 25 firmly in place while a comb, held in the operator's right hand at an approximate forty-five degree angle to the patron's head, is drawn downwardly to either the right or left, according to the desired direction of the wave being produced. 30 Then the second finger of the operator's left hand replaces the first finger and said first finger takes the place of the comb which is raised from the hair. The operator's first and second fingers are then pressed firmly together to impress a crease 35 in the portion of the hair between said fingers and this crease forms the first half of the wave. The second portion of the wave is then produced in like manner, the comb being drawn downwardly in the opposite direction. This procedure is 40 continued for as many waves as desired, the very wet solution holding the hair in the creases which produce the half waves, and the small strands of hair being rolled to produce curls when desired, and the curls being pinned to hold them 45 in place. The next step in the operation is to arrange a hair net on the patron's head after which the patron is prepared for the dryer by placing cotton over her ears to prevent excess heat on the ears.

The dryer employed in waving hair in accordance with the method described above comprises an aluminium hood that fits over the patron's head, and heated air is circulated through 55 this hood in contact with the waved hair for

from thirty to ninety minutes, depending on the texture and thickness of the hair. The use of these dryers is very uncomfortable to the patrons, but in connection with the method of finger waving now followed they are absolutely indispensable, and, also, the circulation of heated air in contact with the hair is very drying and harsh upon the hair. Additionally, the use of the solution on the hair, as explained above, is harmful to the hair, as a dull coating of pulverized seed is left on the hair after the drying operation has removed the moisture from the hair.

In accordance with the use of the invention disclosed herein the use of the solution hereinbefore referred to is entirely eliminated, and also 15 the need for an uncomfortable drying operation is dispensed with. In waving hair in accordance with the present invention the patron's hair is shampooed after which the hair is towel dried, a small amount of moisture being permitted to 20 remain in the hair after the towel drying operation. The hair is then ready for the waving operation without any solution being added thereto, this waving operation being performed in a 25 manner to be hereinafter described. The waving 25 of hair in accordance with this invention, including the shampooing and towel drying operations, consumes approximately thirty minutes, as compared with approximately thirty minutes for 30 shampooing and waving the hair in accordance with the old method, and from thirty to ninety minutes required for the drying operation. This saving of time is of the utmost importance as it permits an operator to handle many more patrons in a day, and additionally, the undesirable 35 results from the use of the solution are eliminated and the discomforts and disadvantages incident to the use of the dryer are dispensed with. Furthermore, a great saving is realized by 40 owners of beauty parlors because of the elimination of the necessity to buy and maintain a number of the rather expensive dryers and provide space therefor.

Fig. 1 is a view illustrating the manner of using the improved hair waving means disclosed herein.

Fig. 2 is a plan view of the improved hair waving means of the present invention.

Fig. 3 is a cross-section of the improved means taken on line 3—3 of Fig. 2.

Fig. 4 is an enlarged fragmentary section taken on line 4—4 of Fig. 3.

Fig. 5 is an enlarged fragmentary section illustrating a modified form of the invention.

ing parts of the improved means of the present invention with a part of the handle of the comb being broken away and showing the hair raising element of the invention associated therewith.

Fig. 7 is a fragmentary end elevation of one of the combs of the improved means of the present invention illustrating one manner of using same when the hair raising element is associated therewith.

Fig. 8 is a modified form of the improved hair waving means of the present invention.

Fig. 9 is an enlarged fragmentary section of an end portion of the comb shown in Fig. 6.

Fig. 10 is an enlarged cross-section of a modified form of the invention.

Fig. 11 is a fragmentary longitudinal section of the structure illustrated in Fig. 10.

In the drawings, wherein are shown for the purpose of illustration, merely, several embodiments of the invention A designates in Figs. 1, 2, and 3 the improved hair waving apparatus of the present invention. The apparatus A comprises a pair of combs 1 and 2 which resemble each other but are slightly different in their details of construction. The comb 1 includes a body portion 3 which in cross-section is preferably of polygonal shape as shown in Fig. 3, from which are extended comb teeth 4, each of said teeth being of substantial width adjacent to the body portion 3 and tapering to a relatively narrow width at its outer end. The body portion 3 and teeth 4 of the comb 1 are made of metal or other suitable material which will conduct heat and the portions of the teeth adjacent to the body portion are made substantially wide so that heat will be properly conducted from the body portion 1 toward the outer ends of the teeth. If desired the outer ends of the teeth may be provided with tips 5 formed of heat insulating material to prevent the outer ends of the teeth from becoming so hot as to cause discomfort to the scalp of a person whose hair is being waved with the aid of the apparatus A. The comb 1 is provided with a handle 6 which is formed of a heat insulating material, said handle being of arcuate shape as shown in Figs. 1 and 2.

The comb 1 has formed in the body portion 3 thereof an opening 7 (Fig. 3) which extends longitudinally of said body portion, said opening being closed at one end of the body portion of the comb and open at the opposite end thereof. Arranged in the opening 7 of the body portion of the comb 1 is an electrical heating unit 8 of well known construction and arrangement, the electrical heating unit 8 having conducting means 9 associated therewith which conducts electrical energy to the electrical heating unit from a suitable source of supply (not shown). The open end of the opening 7 is closed by a suitable cap 10 which is provided with an aperture through which the conducting means 9 extends.

The comb 2 is constructed generally in accordance with the construction of the comb 1 as thus far described; that is to say, the comb 2 is provided with a body portion 11 preferably of polygonal cross-sectional shape in which an opening 12 is formed longitudinally thereof. Also the opening 12 houses an electrical heating unit 13 to which electrical energy is conducted by conducting means 14, and said conducting means extends through an aperture of a cap 15 that closes the open end of the opening 12. Likewise the comb 2 is provided with teeth 16 extended from the body portion 11 of the comb which are

shaped as described in connection with the teeth of the comb 1, and, if desired, the outer ends of the teeth 16 of the comb 2 may be provided with heat insulating tips 17 which serve the purpose of the tips 5 of the teeth of the comb 1. Like the comb 1, the comb 2, except for the tooth tips 17, is formed of metal, or other suitable heat conducting material, and said comb 2 is provided with an arcuate handle 18 which is formed of a suitable heat insulating material.

Unlike the comb 1, the comb 2 is provided at one end with a tapered curler tip 19 which is of polygonal shape in cross-section, said curler tip being formed of heat conducting material. The curler tip 19 has associated therewith a prong 20 which is pivoted at 21 to extension means 22 formed on the curler tip, said prong 20 having associated therewith a suitable spring 23 which serves to move the forward portion of the prong against the curler tip in a manner to clamp and hold hair in contact with said curler tip which has been curled thereon. The prong 20 is provided with an angular extension 24 that provides a thumb piece for moving the forward portion of the prong away from the curler tip against the action of the spring 23, said extension being provided with suitable heat insulating means which permits the extension to be manipulated without danger of the operator being burned.

The combs 1 and 2 are connected together by means of resilient connectors 25 which are preferably located adjacent to opposite ends of the combs as shown to the best advantage in Fig. 2. As shown in the view mentioned, and in Fig. 3, each connector 25 preferably comprises a strip of material whose ends are secured together to provide an elongated loop, the opposite end portions of the elongated loop passing through rings 26 which provide attaching eyes. The attaching eyes 26 of the connectors 25 are engaged by hooks 27 that are suitably secured to the body portions of the combs 1 and 2, the attaching eyes at corresponding ends of the connectors being connected to hooks 27 secured to the comb 1 and the attaching eyes at the opposite corresponding ends of the connectors being connected to hooks 27 secured to the comb 2. The connectors may be formed of any suitable resilient material; for instance they may be formed of latex which is characterized by the ability to stretch and return to an unstretched condition when the force that stretches it is removed.

In the use of the hair waving apparatus A illustrated in Figs. 1, 2, and 3 the patron's hair is shampooed and towel dried, the towel drying being discontinued when the hair is still damp from the shampooing and the hair then being preliminarily combed to prepare it for the waving operation. The hair waving apparatus A is then brought to its operative position with respect to the patron's head, as shown in Fig. 1, the teeth of the combs 1 and 2 being substantially parallel and extended at an angle of approximately forty-five degrees with respect to the perpendicular when the handles of the combs 1 and 2 are aligned with each other as shown in Fig. 3. The electrical energy flowing to the heating units 8 and 13 of the combs 1 and 2 will cause the heat-conducting portions of the combs to be heated, and the comb 2 is applied to the portion of the hair to be waved, just as would the first finger of an operator's left hand when finger waves are made in accordance with the method formerly followed, to hold firmly the hair to be waved. The teeth of the comb 1 are applied to the head

of the patron and said comb 1 is drawn downwardly and to one or the opposite side, depending on the direction of the half wave being produced, thereby drawing the heated teeth of the 5 comb 1 through the hair. When this has been done the heated teeth of the two combs are pressed together, thereby pressing a crease in the hair which is dried in by the heat of the two combs to produce the first half of the wave.

10 The apparatus A is then moved to cause the comb 2 to take the place of the comb 1 and the same procedure is followed, with the exception that the comb 1 is drawn downwardly in the opposite direction. The teeth of the heated combs 15 are then again pressed together to crease and dry the portion of the hair operated on to produce the second half of the wave. This is continued until the desired number of waves have been placed in the hair after which any 20 desired will be produced with the aid of the curling tip 19 and the clamping prong 20 in an obvious manner well known to persons familiar with the art to which this invention relates. It is plain that when the comb is drawn downwardly 25 and to one side with respect to the comb 2 in producing waves as explained above, the connectors 25 will stretch and will return to their normal unstretched condition when the pull on the comb 1 is discontinued.

30 As has been stated the purpose of the tips 5 and 17 at the outer ends of the teeth of the combs 1 and 2 is to prevent the heated teeth from causing discomfort to the scalp of the patron. In this connection, if desired, the teeth of the combs 35 1 and 2 may be provided with apertures 28, as shown in Fig. 5, which will provide the outer end portions of the teeth with air gaps that will interfere with transmission of heat to the extreme outer end portions of the teeth.

40 In some cases of special hair styling it is desired to wave an upper layer of hair over sleek, unwaved hair. This is done without pressing the combs against the scalp and is very difficult to achieve when the method of waving heretofore employed is followed. In order to accomplish this type of waving the combs of the improved apparatus disclosed herein are provided each with the element 29 illustrated in Fig. 6. This element is formed of wire, or like material, 45 arranged in elongated loop form, and the element is applied to the lower portions of the teeth of the comb so that it embraces the entire group of teeth at a point a slight distance inwardly of the outer ends of the teeth as shown in the view 50 menetioned. The opposite end portions of the element 29 are engaged by spring clips 30 as shown in Figs. 6 and 9 so as to hold the element in place on the comb, said spring clips being suitably secured to the heavier end teeth of the comb.

55 60 In the use of the element 29 the upper layer of hair B to be waved is raised with the aid of the comb and the element 29 is introduced under the raised hair as shown in Fig. 7 and is applied to the teeth of the comb as described above. The hair above the element 29 may then be waved in the manner heretofore described with the aid of the improved apparatus A leaving the lower hair C sleek and unwaved. In following this method of waving both of the combs 70 may be provided with elements 29, or, if desired, only the comb 1 may be provided with an element 29.

In Fig. 8 is illustrated a form of the invention where the combs 1 and 2 of the apparatus are 75 connected together by connectors at opposite

ends of the combs (only one end being shown) which are in the form of coil springs 25' attached to eyes 27' secured to the combs 1 and 2. This form of connector is preferred for waving apparatus intended for home use whereby it is undesirable to detach the combs from each other. However, the type of connector 25 shown in Figs. 2 and 3 is preferred in connection with waving apparatus intended for professional use so that the combs may be quickly and easily detached from each other for independent use of the combs.

10 In Figs. 10 and 11 is illustrated a form of the invention where an elongated cavity 31 is provided within the body portion 32 of a comb which serves as a fluid reservoir. The cavity is open at one end of the comb and closed at the opposite end, there being a screw plug 33 provided for sealing the open end of the cavity. Communicating with the cavity 31 is a plurality of 15 apertures 31' which are open at an outer surface of the body portion of the comb, and formed inwardly of the outer surface of the body portion of the comb is an elongated opening that receives an elongated plate 34. The plate 34 is supported 20 for sliding movement within the opening in which it is located, there being angular portions of said plate extended beyond the opposite ends of the body portion of the comb which may be pushed or pulled for sliding the plate longitudinally of 25 its opening, and which serve as stops for the plate. The plate 34 has apertures 34' formed therethrough which are spaced in accordance with the spacing of the apertures 31' leading from the cavity 31 to an outer surface of the 30 body portion of the comb. The plate may be shifted longitudinally of its opening to bring the apertures of said plate in register with the apertures 31', or said plate may be shifted to position the apertures of the plate out of register 35 with respect to the apertures 31'.

In the use of this form of the invention fluid may be introduced into the cavity 31, and because said cavity is in close proximity to the electrical heating element 35 of the comb, the 45 fluid may be generated into steam. When the hair of a patron is too dry or too tightly permanently the plate 34 may be shifted to bring the apertures 34' of the plate 34 into register with the apertures 31' and thus permit steam to be 50 discharged from the cavity 31 onto the hair of the patron.

I claim:

1. An apparatus for waving hair comprising a 55 hair holding element, a comb comprising a body portion and teeth formed of heat-conducting material, an electrical heating unit located within said body portion for heating the comb, and connecting means extensible as to length for connecting said hair-holding element and said comb together for relative movement from each other and relative movement sidewise with respect to each other.

2. An apparatus for waving hair comprising a 65 pair of combs each of which includes a body portion and teeth formed of heat-conducting material, an electrical heating unit located within the body portion of each of said combs for heating the comb, and connecting means for connecting 70 said combs together, said connecting means being extensible as to length and flexible so as to permit one of said combs to be moved away from the other comb and to permit said one of said combs to be moved sidewise relative to said other 75

comb while the combs are connected by said connecting means.

3. An apparatus for waving hair comprising a pair of combs each of which includes a body portion and teeth formed of heat-conducting material, an electrical heating unit located within the body portion of each of said combs for heating the comb, connecting means for connecting said combs together, said connecting means being extensible as to length and flexible so as to permit one of said combs to be moved away from the other comb and to permit said one of said combs to be moved sidewise relative to said other comb while the combs are connected by said connecting means, and a handle associated with each of said combs which is extended at an angle to the axes of the teeth of the comb.

4. An apparatus for waving hair comprising a pair of combs each of which includes a body portion and teeth formed of heat-conducting material, an electrical heating unit located within the body portion of each of said combs for heating the comb, connecting means for connecting said combs together, said connecting means being extensible as to length and flexible so as to permit one of said combs to be moved away from the other comb and to permit said one of said combs to be moved sidewise relative to said other comb while the combs are connected by said connecting means, and means for attaching said connecting means to said combs, said attaching means being of such character as to permit ready detachment of the connecting means from the combs without the aid of tools.

5. A comb adapted for use in dressing hair,

comprising a body portion and teeth which are formed of heat-conducting material, an electrical heating element associated with said comb for heating the teeth thereof, and means for preventing heating of the outer end portions of said teeth of the comb, said means comprising tips formed of heat-insulating material which are supported directly by the teeth of the comb at the outer end portions thereof and constitute the outer end portions of said teeth.

5

10

6. A comb adapted for use in dressing hair, comprising a body portion and teeth which are formed of heat-conducting material, an electrical heating element supported by said body portion of said comb for heating the teeth thereof, and means for preventing heating of the outer end portions of said teeth of the comb, said means comprising tips formed of heat-insulating material which are supported directly by the teeth of the comb at the outer end portions thereof and constitute the outer end portions of said teeth.

15

20

7. A comb adapted for use in dressing hair, comprising a body portion and teeth which are formed of heat-conducting material, said body portion of the comb having an opening formed therein, an electrical heating element extended into said opening of the body portion of the comb for heating the teeth of the comb, and means for preventing heating of the outer end portions of said teeth of said comb, said means comprising tips formed of heat-insulating material which are supported directly by the teeth of the comb at the outer end portions thereof and constitute the outer end portions of said teeth.
